US0D1019840S

(12) **United States Design Patent** (10) **Patent No.:** **US D1,019,840 S**
(45) **Date of Patent:** **** Mar. 26, 2024**

(54) **GOLF CLUB GRIP**

(71) Applicant: **PARSONS XTREME GOLF, LLC,**
Scottsdale, AZ (US)

(72) Inventors: **Daniel C. Kirtley**, Scottsdale, AZ (US);
Raymond C. Gresalfi, Oyster Bay
Cove, NY (US)

(73) Assignee: **PARSONS XTREME GOLF, LLC,**
Scottsdale, AZ (US)

(**) Term: **15 Years**

(21) Appl. No.: **29/851,143**

(22) Filed: **Aug. 25, 2022**

Related U.S. Application Data

(63) Continuation-in-part of application No. 29/844,490,
filed on Jun. 29, 2022.

Primary Examiner — Mitchell I. Siegel

(57) **CLAIM**

The ornamental design for a golf club grip, as shown and described.

DESCRIPTION

FIG. 1 is a top perspective view of a golf club grip;
FIG. 2 is a bottom perspective view of the golf club grip of FIG. 1;
FIG. 3 is a front elevational view of the golf club grip of FIG. 1;
FIG. 4 is a rear elevational view of the golf club grip of FIG. 1;
FIG. 5 is a top view of the golf club grip of FIG. 1;
FIG. 6 is a bottom view of the golf club grip of FIG. 1;
FIG. 7 is a left side view of the golf club grip of FIG. 1; and,
FIG. 8 is a right side view of the golf club grip of FIG. 1.
The broken line shown on the drawings forms no part of the claimed design.

1 Claim, 4 Drawing Sheets
